Grant Elevator Equipment Corporation, Wood-
side, New York, N. Y., a corporation of New
York

Application May 19, 1931, Serial No. 538,569

13 Claims. (Cl. 268—52)

In modern building structures, particularly in congested districts, available space is becoming more and more important and valuable. Moreover in the erection of these structures structural units that can be standardized and yet are utilizable under varying conditions and which can be fabricated at a manufacturing plant and installed as an entity result in material savings in cost both of production and installation.

In connection with the present invention it has been the aim to provide a structure having both of the above advantageous features. In a specific sense the invention relates to improvements in operating and control mechanism for elevator doors, though its range of usefulness is not restricted thereto.

But taking such as an example, it will be readily understood that the less room that is taken for equipment in an elevator shaft or in an elevator car, the more free space becomes available in an area where space at its best is necessarily limited. In addition the regulations regarding the character of this equipment are rigorous both as to character and the availability of the operator to the various controls. It is now common practice to provide the manual means for opening the elevator doors across the same and to place the automatic closing means, check and elevator control switches in the corner of the shaft back of the doors. But this takes up valuable room in the corners, necessitating the cutting down of the size of the cars or hatchway door openings and making it necessary to provide special equipment as toe guards and the like at the door openings and on the doors. In addition the various parts ordinarily have to be separately built and separately installed at the building, making the job when completed an expensive one in addition to the space it occupies.

In the accompanying drawings there are disclosed several embodiments of the present invention particularly intended for elevator doors, and which embodiments may be and preferably are (though not necessarily) built as complete operative units at the manufacturing plant and installed as such in place, the mechanism being peculiarly compact, yet complying with the drastic regulations, but occupying space that has heretofore, so far as I know, been unused and which will not interfere with an elevator car full-sized as compared to the cross sectional area of the shaft in which it operates.

In the accompanying drawings:

Figure 17 is a similar view of the carriage element that operates on said track.

Figure 18 is a view in elevation of the electric interlock switch.

Figure 19 is a detail view in elevation of the locking means and switch operating means when moved to inactive position.

Figure 20 is a side elevation of another embodiment of the invention involving the employment of double doors.

Figure 21 is a vertical sectional view on the line 21—21 of Figure 20.

Figure 22 is a sectional view on the line 22—22 of Figure 21.

Figure 23 is a detail cross sectional view of one of the door carriage members and the track for supporting the carriage of the other door member.

Figure 24 is a longitudinal sectional view through the form of motor and check shown in Figure 1.

Figure 25 is a longitudinal sectional view

through the motor and check structure illustrated in the embodiments of Figures 10 and 20.

Considering first the simplest embodiment of the invention, to-wit, that disclosed in Figures 1-9 inclusive, a support is provided comprising a horizontally disposed plate 26 adapted to be fastened, as indicated at 27, to any suitable portion of the structural frame or casing of an elevator shaft. This plate has an overhanging top wall 28 that terminates in a depending flange 29. An outer or cover wall support 30 is detachably secured to the flange 29 by screws 31 or other suitable fasteners, and may have a rearwardly extending portion 32 that overlies the top wall 28. A casing is thus provided with an open bottom as will be clear particularly by reference to Figure 2. Secured to the plate and located horizontally within the chamber thus formed is a track 33 held in place by screws 34 or other devices and having its upper and lower faces grooved as shown at 35 to provide races for balls 36.

A door hanger carriage reciprocates horizontally on the track 33, and in the embodiment disclosed it consists of an L-shaped plate 37 having an upper rearwardly extending flange 38 and having an angle bar 39 secured to its front face, providing an outwardly extending flange 40. Fastened to the rear side of the carriage plate 37 is a ball race element 41 having rearwardly extending walls that are longitudinally grooved, as illustrated at 42 to receive and allow the travel of the balls 36. A substantially U-shaped ball cage channel plate 43 may be employed, being interposed between the track 33 and ball race element 41 and having openings 44 in which the balls are located. The carriage thus has a free and easy reciprocatory movement on the track 33 and it is provided below said track with brackets 45 socketed to receive and support the heads 46 of pendant bolts 47 held in place by nuts 48 and constituting means for suspending the door 49.

The angle bar 39-40 constitutes a support for a horizontal rack 50 having upstanding teeth. This rack is preferably mounted on posts 51, the posts and rack being secured to the flange 40 of the angle bar by screws 52 passing through the flange 40 and posts 51 and being threaded into the rack. The rack thus is made to reciprocate with the door carriage and door. Another horizontal rack 53 with upstanding teeth is secured to the supporting plate 26 by suitable screws 54.

Fixed in the chamber, for example, by collars 55 suitably secured to the top wall 28 is a door closer motor and check. This consists of a cylinder element 56 horizontally disposed above the track 33 and door carriage 37, and a piston 57 (see Figure 24) that reciprocates in the cylinder and has a piston rod 58 that slidably extends through a packing gland 59 carried by one of the heads 60 of the cylinder element. Secured to the exposed end of the piston rod 58 is a gear case composed of detachably connected sections 61. Extending across this gear case are two shafts 62 and 63. On one is a pinion 64 that is in mesh with a larger gear 65 on the other, this gear and pinion being housed within the gear case 61. One of the shafts as 62 projects on one side of the gear case 61 (see Figure 7), and has detachably fixed thereto a gear 66 that rides the rack 50. The other shaft 63 projects on the opposite side of the gear case 61 and has a gear 67 that correspondingly travels along the rack 53. Located within the cylinder 56 (see Figure 24) are coiled springs 68 that abut the piston 57 and resist its

movement in one direction, while reacting after being compressed, to move said piston in the opposite direction. The cylinder element 56 furthermore holds checking fluid, as oil, which is allowed to travel to opposite sides of the piston. To this end the piston is provided with a passageway 69 extending therethrough from one side to the other and controlled by a ball valve 70 located in a chamber 71 formed in one end of the piston. An open-ended passageway 72 is provided in the cylinder member with ports opening into the piston chamber, allowing the circulation back and forth of the checking medium. Another passageway 73 has an inlet port 74 in the cylinder head 75 and an outlet port 76 into the piston chamber on the opposite side of the piston. The area of the port 74 can be varied by a suitable valve 77.

In the structure as disclosed the door as shown in Figure 1 is in its closed position. To open it, it is manually moved to the left. Upon such movement the rack 50 moves equally with it, thereby rotating the gear 66, and this gear operating through the pinion 64 and gear 65, rotates the gear 67 at a much lower rate of speed, causing the gear 67 to travel along the rack 53. This rack 53 may therefore be relatively short. In fact in actual practice for ordinary purposes it need be but approximately five inches for a large sized door. The piston 57 obviously moves the same distance and consequently the cylinder member 56 can be short. The piston in its movement to the left compresses the springs 68 and the checking fluid which is at the left side of the piston (as seen in Figure 4) will flow freely to the right side through the port 69 and passageways 72 and 73. The door therefore has a relatively unresisted movement except that due to the compression of the springs 68. When the door is released after being opened, the springs 68 are free to react and moving the piston 57 to the right, will correspondingly move the gear case and the gearing carried by it. During this movement, the gear system acts of course to return the door its full movement. In doing so, while the valve 70 of the piston 57 now closes by reason of the pressure of fluid against it during the greater portion of the movement of the piston, the checking fluid can flow freely through the passageway 72 to the rear side of the piston, and a portion of it will also escape through the passageway 73, but after the piston has covered the right hand end of the passageway 72, then the checking fluid that is in advance of the same, can find egress only through the port 74 and this being choked down to any desired degree by the valve 77, the movement of the piston and consequently of the door is slowed down and the latter comes to a quiet stop in its closed position.

It will be noted that this mechanism including the means for hanging any suitable door therefrom, constitutes a complete unit that can be built and assembled at the factory and placed in any desired position. Moreover it is compact and is located above the top of the door and doorway, occupying but little more space than that necessary for the door itself. Furthermore it may be employed for standard doors of various sizes. In other words practically all the elements of the structure can be utilized irrespective of the size of the door within the range now ordinarily employed. The only different elements needed are gears 66 and 67 of different sizes that are readily interchangeable on the shafts 62 and 63. This of course necessitates the adjustment of the

racks 50 and 53, but as indicated in Figure 9a, posts 51 of different lengths may be employed for the rack 50 and the rack 53 can be placed in different positions by providing holes with 5 threaded walls, as shown at 78 for the reception of the screws 54 (see Figure 2).

The structure is also adaptable for use in connection with doors that can be locked in their closed positions and can readily be combined with 10 an electric interlock switch. Such a structure is illustrated in Figures 10-19 inclusive. In Figure 1 a left hand opening door is shown. In Figure 10 a right hand opening door is illustrated. The general structure is however substantially the 15 same as that already explained, and it is believed to be unnecessary therefore to explain the same in detail. The supporting plate is shown at 79 and the track is designated 80. The door hanger carriage is shown at 81 and reciprocates on the 20 track, though in this case a ball cage is not illustrated, it being understood that a cage of this kind may be employed to prevent the displacement or "creeping" of the balls as may occasionally otherwise occur. The carriage 81 has hanger 25 brackets 82, from which is suspended the door 83. The cylinder element is shown at 84 and in this instance is differently constructed, a detail longitudinal section thereof being shown in Figure 25. In this embodiment of the invention the cylinder 30 element includes an extended head 85 provided with a piston chamber 86. The cylinder element proper also has a chamber 87 walled from the piston chamber 86 by a packing gland 88. A piston 89 operates in the piston chamber 35 86 and has fixed thereto a piston rod 90 that extends through the packing gland 88 and through the chamber 87. On its exposed end is mounted a gear case 91 containing the gearing to which are fixed the gears 92 and 93 that respectively 40 travel along the stationary rack 94 and the traveling rack 95, the latter being mounted on the door hanger carriage 81. The door closing spring in this embodiment is shown at 96 in Figure 25 and is located in the chamber 87, being engaged 45 with an abutment collar 97 fixed to the piston rod 90 within said chamber 87. The checking fluid is placed in the piston chamber 86, a plug filling opening 98 being provided for the purpose. The piston has a valved vent 99 similar to 50 that already described, and the piston chamber wall has a by-pass 100. A second by-pass 101, leading from the outer end of the piston chamber 86 to an intermediate portion of the same, is controlled by a valve 102.

The operation of the structure as thus far described is the same as that of the first embodiment, but in this form of closer motor and check, the closer spring does not operate in the chamber containing oil that checks the operation. By referring to Figure 25, however, it will be noted that the diameter of the chamber 87 is greater than the oil check chamber 86, and the chamber 87 provides a receiver for any oil that leaks out of the chamber 86 through the packing gland 88. 65 This is of considerable importance, as it prevents any leakage dripping down on to the door or through the doorway.

In the present embodiment, the door is locked by locking the gear case 91 and piston against 70 movement. To this end pivotally connected toggle links 103 are provided. One of the toggle links is pivoted, as shown at 104 to a bracket 105 adjustably mounted on the supporting plate 79. The other link has in its free end a longitudinal 75 slot 106 in which is engaged a pivot pin 107. The

pivot pin 107 is carried by an ear 108 fixed to the gear case 91. The links are so related that when they are in aligned position they obviously constitute a bar to the movement of the gear case and as the movement of said case is essential to the opening of the door, the door is consequently locked. 5

To allow this movement the following mechanism is preferably employed. An actuating arm 109 is pivotally mounted on a suitable portion of the structure as shown at 110, and at its free end it is provided with an upstanding head 111. The pin 112 that pivotally connects the links is extended so as to rest upon this head 111. The door 83 is provided with a horizontally mounted and 15 horizontally reciprocatory actuating rod 112a, one end being slidably mounted in a bracket 113 and having a head 114 that abuts the bracket to limit the independent movement of the rod with respect to the door. The other end of this rod 20 is connected to one arm of a bell crank 115 located in a casing 116 on the door. The other arm of this bell crank has a connection with a vertically reciprocatory rod 117 adapted to abut against a 25 block 118 carried by the arm 109.

In opening the door the operator grasps the rod 112a and moves it in the direction in which the door is to be opened. The first action causes a movement of said rod 112a with respect to the door, for the door is locked as shown. In this 30 movement the vertical rod 117 is raised thereby swinging the arm 109 upwardly, moving the pivot pin 112 in a corresponding direction and "breaking" the toggle or in other words, causing the links to assume an angular relation as shown in Figure 19. The gear case and piston are now 35 free to move and a continued movement of the actuating rod 112a therefore causes the opening of the door and the continued elevation of the links 103. Upon the return or closing movement of the door under the action of the spring 96, the parts reassume their normal relation and the door automatically locks. 40

The locking and actuating means in this embodiment is also made to constitute operating 45 means for the electric interlock switch. That is to say, it is common practice to require the opening of the motor supply circuit for the elevator when the door of the elevator shaft is opened to prevent any movement of the elevator as long 50 as the door is open. It is believed that this is so well known as to need no exposition beyond a showing of a control switch, and such switch is shown in elevation in Figure 10 and in greater detail in Figure 18. That is to say a casing 120 55 is mounted as shown at 121 on the supporting plate 79. In this casing is a reciprocatory bar 122 of insulating material carrying a contact head 123. Contact arms 124 are pivoted at 125 within the casing and have terminals 126 that are adapted to engage the head 123 when the bar is moved outwardly so as to cause an electrical connection between the arms. These arms as noted are in the controlling or operating circuit. They are urged inwardly by suitable springs 127. 60 When the bar 122 is moved outwardly, the arms 124 will swing towards each other until the heads 126 contact with the head 123. When the bar 65 is moved inwardly in the casing, or to the position shown in Figure 18, the arms 124 are swung outwardly, thus breaking the electrical contact. This movement of the bar is secured by means of a link 128 that is pivoted to said bar and preferably pivoted to the pivot pin 112, which connects the links 103. As long as the links are in their 70 75

aligned or locking position, the bar 122 is in its outermost position, or in other words, the contact heads 126 are in engagement with the head 123 and current can flow freely through the switch, but when the links are raised by operating the actuating rod 112a, upon their initial movement the bar 122 is moved into the casing and the contact is broken, thus opening the switch. In this connection it will be noted that by reason of the slot and pin connection 106-107 of one of the links 103, a limited elevation of the links is permitted before any of the other mechanism is actuated, so that the switch is opened initially before the door is initially moved. This is important as it means the locking of the elevator before the door starts to open.

The structure is also applicable to multiple doors, and such is shown in Figures 20-23 in clusive. Here again it is believed to be unnecessary to go into detail in the general operating structure, as this has been already fully explained. The supporting plate or bar is shown at 129 and carries a track 130 on which reciprocates a door hanger carriage 131 from which is hung one of a pair of double doors, designated respectively 132 and 133. The door 132 operates precisely the same as the door 49 of Figure 1 and the door 83 of Figure 10. In other words the carriage 131, carrying the door 132, has a rack 134 with which meshes a gear 135 forming a part of the set of gearing carried by the gear case 136. Another of these gears 137 meshes with a fixed rack 138 mounted on the supporting plate 129. The gear case 136 is carried by a piston rod 139 operating in a cylinder element 140, all of which is the same as that disclosed in Figure 25. The locking links are shown at 141 and the electric interlock switch at 142, the bar 143 thereof having a link connection 144 with the pivot 145 of the links 141. An actuating arm for the links is shown at 146 and is operated by a vertical rod 147 on the door 133.

The door hanger carriage 131 in this embodiment has fixed to one side another track 148 on which is a hanger carriage 149 that supports the door 133. To effect the movement of the door 133 at twice the rate as the door 132 in order that the door 133 will fully overlap the door 132 when the doors are fully opened, the door hanger 149 has a horizontal rack 150 with its teeth inset. Another oppositely disposed rack 151 is carried by the supporting plate 129 (see Figure 21). These racks are engaged by a gear 152 journaled on the door hanger carriage 131. It will thus be evident that as the carriage 131 moves in either direction, it carries the gear 152 along with it, and this gear running on the track 151 is rotated, thereby causing the rack 150 to travel at twice the speed of the carriage 131, and the rack 150 being fixed to the carriage 149 from which the door 133 is suspended, the latter operates at twice the speed as the door 132. By reference to Figure 21, it will be noted that the balls 153, which create an antifriction bearing for both the carriages 131 and 149, are in ball cages 154 and in order to insure the proper movements of said cages and consequently of the balls the cages 154 are provided with racks 155 that are engaged by a gear 156 fixed to the gear 152.

The same advantageous features as set out with respect to the first described embodiment will be found in the other two forms of construction, and in addition the locking means and the control switch are intimately associated with the

parts and occupy unobstructed and heretofore unused space above the doors.

From the foregoing, it is thought that the construction, operation and many advantages of the herein described invention will be apparent to those skilled in the art without further description, and it will be understood that various changes in the size, shape, proportion and minor details of construction may be resorted to without departing from the spirit or sacrificing any of the advantages of the invention.

What I claim, is:

1. The combination with a reciprocatory closure, of a rack mounted thereon, a fixed rack adjacent the closure, a motor element including a movable element, a gear case carried by the movable element, coacting gears in the gear case, and gears connected to said coacting gears and respectively engaging the racks.

2. The combination with a reciprocatory closure, of a rack adjustably mounted thereon, a fixed rack adjustably mounted adjacent the closure, a motor element including a movable element, a gear case carried by the movable element, coacting gears in the gear casing, and interchangeable gears adapted to be connected to said coacting gears and respectively engaging the racks.

3. A closure operating unit comprising a supporting plate, a horizontal track thereon, a hanger carriage that travels on the track and has depending brackets for suspending a door, a rack fixed to the carriage, a rack fixed to the supporting plate, a cylinder fixed to the supporting plate longitudinally of the track and above the same, a piston in the cylinder, a gear case moved by the piston, intermeshing gears in the gear case, and gears externally of the gear case and connected to the other gears, said external gears being engaged respectively with the racks.

4. The combination with reciprocatory doors movable horizontally to and from an overlapping relationship, of movable carriages above the doors and from which the doors are suspended, a support for the carriages above the doors, a rack carried by the support, a rack on one of the door carriages, a gear between the racks, a rack on the other carriage, a second rack mounted on the support, gearing between the latter racks, and motor means for moving the gears and thereby the doors.

5. The combination with a support, of a track thereon, a door hanger that reciprocates on the track, a track mounted on and reciprocable with the door hanger, a second door hanger that reciprocates on the reciprocable track, gearing between the second door hanger and support to cause its movement at a greater rate of speed than the first hanger, a cylinder mounted on the support, a piston operating in the cylinder longitudinally of the tracks, and gears movable with the piston and respectively engaged with the support and with the first hanger to cause the latter to move at a greater rate of speed than the piston.

6. The combination with a support, of a track thereon, a door hanger that reciprocates on the track, a track mounted on and reciprocable with the door hanger, a second door hanger that reciprocates on the reciprocable track, a rack on the second door hanger, a rack on the support, a gear on the first door hanger that engages the racks, to cause the second door hanger to move at a greater rate of speed than the first hanger, a cylinder mounted on the support, a piston operat-

ing in the cylinder longitudinally of the tracks, a second rack on the support, a rack on the first door hanger, and gears carried by the piston and respectively engaged with the two last mentioned racks to cause the first door hanger to move at a greater rate of speed than the piston.

7. The combination with a support, of a track bar fixed to the lower portion thereof, a door hanger carriage that reciprocates on the track, a cylinder mounted on the support above and longitudinally of the track, a piston that operates in the cylinder, a rack mounted on the carriage, a rack mounted on the support, a gear case moved by the piston and having gears meshing with the racks, a second track mounted on the door hanger carriage, a second door hanger carriage that reciprocates on the second track, a rack on the second carriage, a second rack on the support, and gearing on the first carriage in mesh with the latter racks.

8. The combination with a support, of a reciprocating door hanger carriage movable thereon, a door hung from and movable with the carriage, pivotally connected toggle links above the door and movable to and from a relation for holding the door and carriage, and means for moving the toggle links from their holding relation including an operating device movably mounted on and movable with the door.

9. The combination with a support, of a reciprocating door hanger carriage movable thereon, a door hung from and movable with the carriage, pivotally connected toggle links above the door and movable to and from a relation for holding the door and carriage, an actuating arm mounted on the support and acting on the toggle links to move them from their holding relation, and a device movably mounted on the door and movable therewith, said device being adapted to engage with the arm when the door is locked to move said arm and thereby move the links from their holding position.

10. The combination with a support having a track, of a door supporting carriage that reciprocates on the track, a rack on the carriage, a rack

on the support, a motor member including a movable drive element, gearing on the drive element that is engaged with the rack, pivotally connected links pivoted to the support and drive element and adapted to move to a relation to hold said element and thereby the door against movement, and an arm pivotally mounted on the support and engaged with the links at their connections to swing them from their holding relation.

11. The combination with a support having a track, of a door supporting carriage that reciprocates on the track, a door hung from the carriage, a rack on the support, a motor member including a movable drive element, gearing on the drive element that is engaged with the rack, pivotally connected links pivoted to the support and drive element and adapted to move to a relation to hold said element and thereby the door against movement, an arm pivotally mounted on the support and engaged with the links to swing them from their holding relation, and means for swinging the arm including a reciprocating rod mounted on the door.

12. The combination with an elevator or like door, of mechanism for automatically moving the door to closed position, a lock associated with the closing mechanism to hold the same and the door against opening, and means movably mounted on the door to initially actuate the lock and thereafter move the door to open position, said means moving with the door into and out of position to actuate the lock.

13. The combination with an elevator or like door, of mechanism at the top of the door for automatically moving the door to closed position, a lock at the top of the door associated with the closing mechanism to hold the same and the door against opening, and means movably mounted on the door and movable therewith to and from a position to engage with the lock to actuate the lock.

NATHAN A. GUSSACK.
